TELEVISION RECEIVER BASE

Murray J. Abeles and Clarence A. Troutman,
High Point, N. C.

Application January 18, 1955, Serial No. 34,036

Term of patent 7 years

(Cl. D56—4)

FIG-1

FIG-2

FIG-3

FIG-4

To all whom it may concern:

Be it known that we, Murray J. Abeles, a citizen of the United States, residing at High Point, in the county of Guilford and State of North Carolina, and Clarence A. Troutman, a citizen of the United States, residing at High Point, in the county of Guilford and State of North Carolina, have invented a new, original, and ornamental Design for a Television Receiver Base, of which the following is a specification, reference being had to the accompanying drawing, forming a part hereof.

Figure 1 is a front perspective view of a television receiver base showing our new design, a door being shown in an open position;

Figure 2 is a rear perspective view thereof;

Figure 3 is a top plan view thereof; and Figure 4 is a bottom plan view thereof.

We claim:

The ornamental design for a television receiver base, as shown.
